UNITED STATES PATENT OFFICE.

JAMES WADE, OF PALMER, MASSACHUSETTS.

DESIGN FOR A CARPET PATTERN.

Specification forming part of Design No. 5,409, dated December 12, 1871.

To all whom it may concern:

Be it known that I, JAMES WADE, of Palmer, in the county of Hampden and State of Massachusetts, have invented or produced a new and original Design to be inwrought into Brussels and other Carpeting in suitable colors; and I do hereby declare that the photographs accompanying this specification do give a description of the nature of my invention sufficient to enable any one skilled in the art of carpet-weaving to use my invention.

What I claim as my invention, and desire to secure by Letters Patent, is—

The configuration of the design hereunto annexed, when applied to carpeting in the form similar to the drawings or photographs accompanying this specification.

JAMES WADE.
